UNITED STATES PATENT OFFICE.

JOHN O. DAVIS, OF MINNEAPOLIS, MINNESOTA, AND JESSE H. STICE, OF TAMA, IOWA;
SAID STICE ASSIGNOR TO SAID DAVIS.

LEGAL-BLANK-VENDING MACHINE.

1,407,842.

Specification of Letters Patent. Patented Feb. 28, 1922.

Application filed December 15, 1920. Serial No. 430,942.

To all whom it may concern:

Be it known that we, JOHN O. DAVIS and JESSE H. STICE, are citizens of the United States, residing, respectively, at Minneapolis and Tama, in the counties of Hennepin and Tama and States of Minnesota and Iowa, have invented certain new and useful Improvements in Legal-Blank-Vending Machines; and we do hereby declare the following to be a full, clear, and exact description of the invention, such as will enable others skilled in the art to which it appertains to make and use the same.

Our invention has for its object to provide an extremely simple and highly efficient vending machine or device especially adapted for use in connection with coin-actuated mechanism, for delivering to the purchaser, one at a time, legal blanks or like paper sheets, and to such ends, generally stated, the invention consists of the novel devices, construction and arrangement of parts hereinafter described and defined in the claims.

25 In the accompanying drawings, which illustrate the invention, like characters indicate like parts throughout the several views.

Referring to the drawings:

Fig. 1 is a front elevation with some parts broken away and some parts in vertical transverse section;

30 Fig. 1^a is a fragmentary enlarged section on the same line as the upper portion of Fig. 2, but illustrating a slightly modified construction;

Fig. 2 is a vertical longitudinal section taken on the line 2—2 of Fig. 1;

Fig. 3 is a horizontal section;

40 Fig. 4 is a perspective showing one of the drawers with the co-operating devices carried thereby, removed from working position;

Fig. 5 is a fragmentary side elevation of one of the drawers; and

45 Figs. 6 and 7 are details in section approximately on the line 6—7 of Fig. 3, the former showing the feed roller in normal position and the latter showing the same in the act of feeding or delivering a blank.

50 So far as the broad idea of this invention is concerned, the machine or device may involve any desired number of units or sections, but preferably, it will involve a plurality of such units or sections all incorporated into a common cabinet or casing and

each unit operating to deliver one type of several different kinds of blanks, which may not only differ in character, but may sell at different prices.

The cabinet 8 illustrated is shown as 60 formed with vertically spaced drawer compartments 9 and with intervening horizontal partitions 10, but, of course, the cabinet may be provided with a plurality of such vertical rows of compartments. 65

Below the lower compartment 9, the cabinet is shown as provided with a coin compartment 11, into which the coins may drop, as hereinafter described, through large vertically aligned openings 12 in the partitions 10 at one side of the cabinet, (see Fig. 1). In front of the respective compartments 9, the front wall of the cabinet 8 is provided with narrow horizontally extended blank delivery passages 13, and at its rear, said cabinet is preferably provided with a large hinged door 8^a that may normally be held closed by a suitable lock, not shown. 75

Slidably seated within each compartment 9 and held against lateral displacement by 80 guide cleats 14 on the horizontal partitions 10, are drawers or flanged slides 15 preferably formed of sheet metal and left open or flangeless at their rear ends.

Within each drawer 15, is a table 16, preferably made of sheet metal and having upturned side flanges through which and the side flanges of the drawer a rod 17 is preferably passed to afford a pivotal connection between the two. This pivot, for an important reason to be hereinafter further considered, is located rearward of the center of gravity of the table. 85 90

The legal blanks, or like sheets *y*, are placed on the several pivoted tables, and the several different stacks thereof may be of different kind or character.

Means is provided for yieldingly forcing downward the relatively light rear end of each table 16; and as shown, this means consists of a coiled spring 18, a screw bolt 19 and a nut 20. The spring 18, at its lower end, is anchored to the co-operating drawer 15. The bolt 19 is passed through an arm 21 secured to and projecting rearward from the co-operating table 16. The nut 20 works on top of said arm and is adjustable to vary the tension of the spring 18. 100 105

The numeral 22 indicates a feed shaft journaled in the side flanges of the table 15. 110

and overlying the front end portion of the pivoted table 16, the side flanges of said table being notched so as to clear said shaft and at no time to engage said shaft. Secured on each shaft, above the stack of sheets or blanks y , are several, (as shown, three), feed rollers 23 against which the forward portion of the top sheet or blank is pressed into frictional contact by the spring 18. The rollers 23 are preferably of metal and are provided with peripheral facings, of rubber or similar material 24, which extend less than completely around said rollers, leaving gaps that expose smooth and relatively slippery portions of the rollers in contact with said upper sheet y , when said rollers are in normal position shown in Figs. 1 and 6.

Secured on the front of each drawer 15 is a so-called throat piece 25, which has a forwardly converging throat passage 26, the lower surface of which is covered with an inclined deflector 27, of rubber or similar material, that will have a frictional retarding action on the sheets fed against the same. The contracted outer portions of the throats 26 align with the delivery passages 13 and with passages in the front flange of the respective drawers. This exact relation of these parts will be more fully noted in the description of the operation.

Advisably, a money drawer is placed in the lowermost or money compartment 11.

The feed shafts 22, at one end, are threaded and detachably engageable with the internally threaded ends of stub shafts 28 that are slidably journaled in bearing plates 29 secured on one side of the cabinet or main casing 8. At their outer ends, the stub shafts 28 have operating knobs 30.

For controlling the delivery of the blanks or sheets to the purchasers, any suitable coin mechanism may be employed, but for convenience, we have illustrated a coin mechanism which is the sole invention of Jesse H. Stice, one of the applicants herein, and which coin mechanism, briefly described, is as follows: The numeral 31 indicates a ratchet wheel secured to each feed shaft adjacent to its threaded end and prevented from backward rotation by a retaining dog 32 pivoted to the adjacent side of the corresponding drawer 15. The numeral 33 indicates a lock lever pivoted to the side of the drawer 15 at 34 and, at its long relatively heavy end, having a depending hook that engages a lug 35 on the hub of the ratchet wheel 31, and normally prevents rotation of the feed shaft 22 in the direction of the arrow marked on Fig. 5. The short ends of said several lock levers 33 stand slightly under co-operating coin chutes 36 that are secured to and extend through the front plate of the cabinet 8. On each ratchet wheel 31 is a stop pin 37 that normally closely overlies the long end of the co-operating lock lever 33. The

numeral 38 indicates cam strips secured to the inner surfaces of the sides of the cabinet 8 and serving to press the front ends of the drawers down to position, when the drawers are inserted to working positions. The character a , Fig. 2, indicates a coin.

Operation.

The operation of the device described, briefly summarized, is substantially as follows:

As already noted, the forward portion of the top sheet y will be pressed into contact with the overlying co-operating feed rollers 23. When there is a large number of sheets y on a particular table 16, the front end of the table will be pressed farther downward and the co-operating spring 19 will be stretched and put under greater tension than when there are but a few of such sheets y on a table. However, in view of the fact that the pivot 17, which supports the table, is rearward of the center of gravity, it is evident that the greater the number of leaves or sheets y on the table, the greater will be the excess of weight of the leaves forward than rearward of said pivot. The pivot is so located that this excessive weight of the forward portions of the stack of leaves or blank sheets will exactly or approximately offset the increased tension of the spring due to downward movement of the front and upward movement of the rear end of the table. Hence, regardless of the number of leaves or blanks on the table, the pressure of the top leaf against the feed rollers will always be approximately the same. This is important, because the pressure should be so adjusted that the rubber or frictional facings on the rollers will properly feed off the top sheet or blank without moving the sheet or blank next to the top, and this requires quite fine adjustment, which should be maintained under all the conditions under which the sheets or blanks must be fed.

Normally, the feed shaft 22 and feed rollers 23 are locked, so that they cannot be rotated, by the engagement of the hook-like end of the lock lever 33 with the lock lug 35 of the ratchet wheel 31, and hence, normally, no feeding movement of the blanks can be produced.

When the proper coin a is deposited in the chute 36, it will fall onto and be intercepted by the short end of the lock lever 33 and will lift the long end of said lock lever against the pin 37, thereby releasing the lug 35 and permitting the ratchet wheel 31, feed shaft 32 and feed rollers 33 to be given one complete rotation whereupon said lock lever will again lock said shaft and said rollers. When the ratchet wheel and said shaft are rotated, as just described, the coin will drop from its dotted line position, Fig. 5, 130

out of the chute and into the coin box 11. Fig. 2, at the top section, illustrates the fact that the top sheet is always in line for projection directly against the upper portion 5 of the inclined frictional retarding surface 27.

The above noted rotation of the feed shaft and its feed rollers will feed the top sheet or blank out through the throat passage 26 10 and the delivery passage 13, substantially to the position shown at the top in Fig. 2, so that said sheet may then be engaged by a finger and thumb and readily pulled completely out of the cabinet. In this latter 15 noted pulling action of the sheet or blank, it is important to note that it is pulled against the smooth portions of the underlying feed rollers 23.

With the arrangement described, it is evident 20 that any one of the several so-called drawers, with the mechanism applied thereto, may be readily removed, for the purpose of applying a new supply of blanks therein and then may be readily replaced. As before indicated, the stub shafts 28 must be 25 unscrewed from the co-operating feed shafts 22, before the drawers may be removed, as above described.

In Fig. 1^a, the partitions 10^a are set obliquely inclining forward toward the discharge throats 26. This positions the sheets 30 γ at a very steep angle and is highly important because it causes the sheets to lie loose, as distinguished from compact or 35 tightly pressed together. In practice, it has been found that, by thus supporting the sheets, the tendency of the sheets to stick together and to feed out two or more at a time is very greatly lessened and, in fact, 40 almost entirely overcome. When the sheets are tightly pressed together, they will frequently be caused to stick or adhere, probably partly by friction, partly by partial vacuum and partly by static electricity. 45 Moreover, the sheets inclined toward the delivery throat will feed off from the top of the stack more easily than where the sheets are located horizontally or nearly so.

This invention, as is evident, affords an 50 extremely simple and efficient vending mechanism for legal blanks and various other papers or like sheets.

It will, of course, be understood that this mechanism is capable of modification within 55 the scope of our invention, as herein described.

What we claim is:

1. A vending machine comprising an enclosing case, a tilting sheet-supporting table 60 removable into and out of said case, a feed roller overlying one end of said table and against which sheets on said table are arranged to be pressed, and means for locking and releasing said feed roller.

65 2. A vending machine comprising an en-

closing case, a drawer in said case, a sheet-supporting table movably mounted within said drawer, a feed roller overlying one end of said table and against which sheets on said table are arranged to be pressed, 70 and means for locking and releasing said feed roller, said case having an elongated delivery passage through which the sheets are adapted to be fed, one at a time.

3. A vending machine comprising an enclosing case, a drawer in said case, a sheet-supporting table pivoted to said drawer, a feed roller overlying one end of said table and against which sheets on said table are arranged to be pressed, means for locking 75 and releasing said feed roller, and means operative on the table for yieldingly pressing the top sheet against the roller.

4. A vending machine comprising an enclosing case, a tilting sheet-supporting table 80 movable into and out of said case, a feed roller overlying one end of said table and against which sheets on said table are arranged to be pressed, means for locking and releasing said feed roller, and a roller-operating element exposed at the exterior of said case and detachably connected to said feed roller.

5. A vending machine comprising an enclosing case, a sheet-supporting table pivotally mounted within said case, a feed roller overlying one end of said table and against which sheets on said table are arranged to be pressed, and means for locking and releasing said feed roller, said feed roller having a smooth segmental peripheral friction surface formed with a gap that normally presents the smooth portion of said roller 90 against the top sheet on said table.

6. A vending machine comprising an enclosing case, a drawer removably mounted in said case, a feed table movably mounted in said drawer, a feed roller journaled to said drawer and overlying the front portion of said table, and a spring connecting said table to said drawer for yieldingly pressing the front portion of the top sheet against said feed roller, said case having a delivery passage through which the sheets are adapted to be fed, one at a time.

7. A vending machine comprising an enclosed case, a drawer in said case, a sheet supporting table intermediately pivoted to said drawer, a feed roller overlying one end of said table and against which sheets on said table are arranged to be pressed, means for locking and releasing said feed roller, and means operative on the table for yieldingly pressing the top sheet against the roller.

8. In a vending machine, the combination with an enclosing case, of a drawer movably mounted therein, a feed table supported from said drawer by an intermediate pivot located rearward of its center of gravity, a 130

feed roller overlying the front portion of said table, and a tension spring connecting the rear portions of said table and drawer and operative to press the front portion of 5 the top sheet on said table against said feed roller, said case having an elongated delivery passage through which the sheets from said table are adapted to be fed, one at a time.

9. The combination with a case having a 10 plurality of vertically spaced compartments, drawers independently mounted in the several compartments, sheet-supporting feed tables in the several drawers, independently operative feed rollers overlying the several 15 feed tables, means operative on said tables for independently pressing the top sheets contained thereon against the co-operating feed rollers, said case having delivery passages through which the sheets from the several feed tables are adapted to be fed, one 20 at a time, roller-operating devices exposed

at the exterior of said case and independently detachably connected to the respective feed rollers, and common means for normally holding several drawers within said 25 case.

10. A vending machine comprising an enclosing case having a plurality of superimposed drawer compartments with forwardly inclined bottoms and with elongated 30 delivery passages adjacent the lower ends of said compartments, drawers displaceably mounted in said compartments, sheet-supporting feed tables mounted in said drawers, and feed devices applied to said drawers 35 and operative to feed the top sheets from said tables, one at a time.

In testimony whereof we affix our signatures.

JOHN O. DAVIS,
JESSE H. STICE.
